UNITED STATES PATENT OFFICE.

JOHN A. MILLER, OF CHICAGO, ILLINOIS.

APPARATUS FOR STEAMING VELVET, SILK, LACES, OR LIKE MATERIALS.

SPECIFICATION forming part of Letters Patent No. 762,333, dated June 14, 1904.

Application filed February 13, 1902. Serial No. 93,870. (No model.)

To all whom it may concern:

Be it known that I, JOHN A. MILLER, a citizen of the United States, residing at Chicago, county of Cook, State of Illinois, have invented certain new and useful Improvements in Apparatus for Steaming Velvet, Silk, Laces, or Like Materials, of which I do declare the following to be a full, clear, and exact description, reference being had to the accompanying drawings, forming part of this specification.

This invention has for its object to provide improved means whereby velvet, silk, laces, or like materials that have become creased or the appearance of which has become impaired may be steamed in order that the creases may be removed and a fresh appearance may be given to such articles. When velvet, for example, has been worn for a considerable length of time, it is apt to become creased and to have the nap pressed flat and rubbed, thereby causing the velvet to seem worn or old long before it has been seriously impaired. By steaming and brushing such velvet the nap can be caused to resume its normal position, so that the velvet after the steaming operation shall appear like new. Velvet has heretofore been steamed by placing a damp cloth over the face of an ordinary sad-iron and laying the velvet upon the cloth; but as the ordinary sad-iron when placed on end stands in an approximately vertical position and is not held against lateral movement it is difficult for the operator to retain the velvet upon the iron with one hand while brushing the nap with the other. Moreover, the ordinary sad-iron is formed with sharp angular edges, which are apt to leave creases in the velvet, notwithstanding the interposition of the damp cloth between the velvet and the iron.

My invention has for its object to provide means whereby velvet and like materials may be steamed; and the invention consists in the features of improvement hereinafter described, illustrated in the drawings, and particularly defined in the claim at the end of this specification.

Figure 1 is a perspective view showing the

stand with the steaming-iron in position for use. Fig. 2 is a plan view of the stand.

A designates my steaming-iron, the base of which extends at right angles to the sides, while the front or upper end of the iron is rounded. The working face *a* of the iron has its edges rounded, as at *a'*. The iron A is provided with a handle B, suitably connected to the body of the iron. The handle B of the iron is adapted to set within a suitable seat or opening *c*, that is formed in the top plate of the stand or base C. The top plate of the stand C is sufficiently raised to permit the handle B of the iron to pass through the top plate. The top plate of the stand is preferably flat or is so shaped as to form a rest for the end of the iron-body. The opening *c* in the top of the base is preferably an elongated opening, so as to receive the handle B, the lower portion of the handle when within the opening bearing against the bottom of the opening and aiding in rigidly holding the iron in position. The end of the opening *c* toward the base of the iron is contracted, so as to better grip the narrow part of the handle when the latter is set within the opening. The iron having been heated in the usual manner will be placed upon the stand in the position shown in Fig. 1 of the drawings, the handle B of the iron setting within the opening *c* of the stand and being securely held thereby. When in this position, the working face of the iron will be at an angle of about forty-five degrees, so that a damp cloth and the velvet placed thereon will not readily slide down off the iron.

In steaming velvet or like material the operator will place the heated iron in the position shown in Fig. 1 and will then lay a damp cloth over the face of the iron, and having placed the velvet upon the cloth, with the nap side of the velvet uppermost, will lightly brush the nap with a suitable brush, so as to cause the nap while subjected to the steam rising from the cloth to assume its normal position. The operator will advance the velvet and from time to time also the damp cloth to expose new surfaces to the steaming operation of the iron. Inasmuch as the working

face of the iron has rounded edges all danger is avoided of forming creases in the velvet or like material as it is being steamed.

Having thus described the invention, what 5 I claim as new is—

A support for holding a sad-iron for steaming velvet or the like consisting of a base having a raised top plate provided with an elongated opening, both ends of said opening being closed, one of the closed ends of said open-

ing serving as a rest for the handle of the sad-iron to hold said iron in inclined position and the other end of said opening being contracted and serving to grip the handle of the sad-iron and hold the iron against lateral movement. 15
